WELT HOLDING MECHANISM

William C. Card, Jr., Winthrop, Mass., assignor
to Compo Shoe Machinery Corporation, New
York, N. Y., a corporation of Delaware

Application October 19, 1934, Serial No. 748,980

10 Claims. (Cl. 12—33)

This invention relates to the manufacture of shoes, and more particularly to an apparatus for holding down the welt extension of a shoe when pressure is applied to its bottom, as during a channel laying or sole affixing operation.

A general object of the invention is to provide an improved welt hold-down apparatus to be used in conjunction with pressure applying devices such as sole presses and the like.

10 More particularly, the invention has for objects the provision of advantages in an inflatable shoe press equipped with a welt hold-down device such as ease of operation and control, ready adjustability, compactness and relative 15 simplicity and inexpensiveness in structure, ease of assembly and disassembly for the purpose of utilizing variously sized welt crease platens and general practicality and satisfaction in operation.

Other objects of the invention will in part be 20 obvious and will in part appear hereinafter.

The invention accordingly comprises the features of construction, combination of elements, and arrangement of parts which will be exemplified in the construction hereinafter set forth 25 and the scope of the application of which will be indicated in the claims.

For a fuller understanding of the nature and 30 objects of the invention reference should be had to the following detailed description taken in connection with the accompanying drawings, in which:

Fig. 1 is a side elevation of a shoe press equipped 35 with one form of a welt hold-down device constructed in accordance with the principles of the present invention, the lower portion of the press being shown in medial vertical section;

Fig. 2 is a horizontal sectional view corresponding substantially with line 2—2 of Fig. 1, the shoe being unmoved;

40 Fig. 3 is a fragmentary horizontal sectional view taken along line 3—3 of Fig. 1;

Fig. 4 is a fragmentary transverse vertical sectional view taken along line 4—4 of Fig. 3;

Fig. 5 is a fragmentary vertical sectional view, 45 on a slightly enlarged scale, showing details at the forward part of the welt hold-down apparatus; and

Fig. 6 is a fragmentary exploded perspective view showing details of the welt hold-down platen joint structure.

A very satisfactory type of cemented shoe can be made by following the lasting operations customarily used in the manufacture of sewed welt shoes up until the time of applying the outer sole, which latter then is cemented to the welt on

the upper instead of being stitched thereto. Such cement affixing operation takes place in an inflatable press of the kind customarily used in the application of outer soles to cemented shoes. When pressure is thus applied to the bottom 5 of the outer sole, it is desirable that some means of support be given the welt extension which projects beyond the body of the upper in order to prevent this extension from being rolled or curved by the pressure pad and also to assure firm cement adhesion between such extension and the outer sole. Such a supporting means also is desirable in sole affixing ordinary cemented shoes which are not equipped with a welt in order to prevent rolling of the sole extension. 10 15

In channel laying operations on sewed shoes, it is also desirable to support the welt extension against pressure applied to the bottom of the outer sole in laying the channel.

The present device is intended to provide such 20 a welt extension supporting means and is useful in any operation such as those mentioned. Accordingly, while for convenience of reference terms such as "welt extension" and "welt crease" are used in the present description and claims, 25 it is intended that these terms shall, wherever the context permits, refer to that marginal portion of the outer sole which is not directly backed up by the upper, regardless of whether or not a welt actually is used in the shoe construction. 30

Referring more particularly to the drawings, there is shown an inflatable shoe press having a base portion 10 and a rigid bow member 11 from which extend a toe post 12 and heel post 13. The press has an inflatable pressure applying pad 14 positioned in its base portion.

At the forward end of base 10 there are provided a plurality of approximately vertically extending spring pockets 15 (Figs. 1 and 4) which preferably are cast integrally with the press casting. If desired, however, these pockets may be separately applied to the press in any suitable manner, in which case the welt hold-down apparatus about to be described may be applied to existing presses which were not heretofore 40 so equipped. The spring pockets 15 each have an opening 16 passing therethrough, which opening is enlarged as at 17 (Fig. 4), and slidably accommodates a rod 18. The lower end of each rod 18 has threaded thereon a spring seat or 45 head 19 which is snugly slidable within the enlarged opening or pocket at 11. A compression spring 20 is located between each head 19 and the upper end of its respective pocket. This spring gives each rod 18 a normal downward 50 55

bias and the upper end of each rod is provided with a head 21 which bears against a welt hold-down housing generally designated 22.

This housing comprises an upper confining plate 23 and a lower confining plate 24, both of which are suitably configured to overlie the forward portion of the press and each of which has a rearward U-shaped recess accommodating the forepart of a shoe. The upper plate 23 5 has a downwardly extending marginal rib 25 (Fig. 4) which serves to space lower plate 24 10 therefrom.

A pair of welt crease engaging platens are 15 slidably accommodated within the space between the upper and lower housing plates. These platens are respectively designated 26 and 27 and their inner edges are shaped so as to fit within the welt crease of a shoe located on the press and to bear against the welt extension of its outer sole. 20 The platens are pivotally joined at their forward ends, each being medially undercut as is best shown at 28 and 29 in Fig. 6 so as to provide a continuous welt engaging surface around the toe end of the shoe in any adjusted position 25 of the platens. A pivot pin 29 extends from one of the platens into a pivot bearing 30 in the other. As shown in Fig. 6, platen 26 is coped at 31 and that portion of platen 27 which overlies this coped area is provided with a pin hole 32, into 30 which is fitted a pin 33, which in turn is carried by a link 34 that is pivotally attached to an operating lever 35. Lever 35 is pivoted at 36 so as to swing between the housing plates and its free end is provided with an upwardly projecting 35 operating handle 37, which is movable along a slot 38 provided in the upper housing plate. Adjacent their free or rearward ends, the platens are respectively provided with guide slots 39 and 40, into which project fixed guide pins 41 and 42. 40 These pins are threaded downwardly into upper housing plate 23 so as to have their lower ends project within the space between the housing plates and each pin has its upper end provided with a knurled head to facilitate ready insertion 45 and removal thereof. The pin 33 which serves as a connection between the operating lever 35 and the pivoted platens has a downward extension 33' which is slidable along a guide groove 43 provided in the lower housing plate 24.

50 The entire arrangement is such that forward and backward movement of operating lever handle 37 causes forward and backward movement of the platens 26 and 27, such movement being guided adjacent their pivotal joint by the pin 33' and the groove 43 and being controlled by the 55 guide pins and slots 39, 40, 41 and 42 so as to cause a mutual approach and recession of the platens as they move backward or forward. In other words, the platens are adapted to contract 60 about the forepart of a shoe.

It will be seen that the entire spring housing is yieldably mounted as a unit on the press, spring pressed movement of such housing being permitted by the slidable rods 18.

65 Preferably each platen is provided with a rather highly compressible rubber buffer 44 which is adapted to abut against the toe of a shoe and to cushion the application of the platens to the welt crease thereof.

70 The platens 26 and 27 are confined against vertical movement by the housing 22 which snugly embraces them while permitting horizontal sliding movement. These platens also are readily removable from the housing, it being necessary only 75 to unscrew the guide pins 41 and 42 sufficiently to

retract them from the grooves 39 and 40, and to withdraw the platens sufficiently to clear pin 33 from beneath the upper housing plate 23. The platens may then be slid from between the housing plates and replaced by others of different size 5 when this is desirable in order to accommodate shoes having a considerable size variation from those previously handled.

In operation the lever 35 is normally held in a forward position so that the platens are expanded. 10 A shoe is loaded in the press in the ordinary manner, being properly positioned beneath posts 12 and 13 and above the pressure pad 14. The operating handle 35 is then moved toward the heel end of the press so as to contract the platens 15 about the forepart of the shoe, the operator seeing that they enter into the welt crease thereof so as to be in supporting relation with the sole extension. The inflatable pad is then blown up so that pressure is applied to the bottom of the 20 sole, such pressure being counteracted in the welt extension area by the platens 26 and 27.

It will be seen that there has been provided an apparatus which is well suited to fulfil its intended functions. Since certain changes may be 25 made in the above construction and different embodiments of the invention could be made without departing from the scope thereof, it is intended that all matter contained in the above description or shown in the accompanying drawings 30 shall be interpreted as illustrative and not in a limiting sense.

It is also to be understood that the following 35 claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. In a shoe apparatus having means for applying pressure to the bottom of a shoe, a welt hold-down device comprising a housing having upper and lower confining plates, platens slidably mounted between said plates in position to engage in the welt crease of a shoe positioned on said apparatus, said plates confining said platens against vertical movement with respect thereto, and means for sliding said platens in said housing to accommodate shoes of varying sizes.

2. In a shoe apparatus having means for applying pressure to the bottom of a shoe, a welt hold-down device comprising a housing having upper and lower confining plates, platens slidably mounted between said plates in position to engage in the welt crease of a shoe positioned on said apparatus, said plates confining said platens against vertical movement with respect thereto, means for sliding said platens in said housing to accommodate shoes of varying sizes, and spring 60 means normally urging said housing toward said pressure applying means.

3. A shoe press having a base, means for applying pressure to the bottom of a shoe, and means for supporting the shoe against such pressure, a housing at the toe end of said base, spring means resiliently anchoring said housing to said base with a normal bias toward said pressure applying means, and platen members slidably mounted in said housing in position to engage in the welt 70 crease of a shoe located in said press.

4. A shoe press having a base, means for applying pressure to the bottom of a shoe and means for supporting the shoe against such pressure, a housing at the toe end of said base, said base 75

having spring pockets, rods extending from said housing respectively into said pockets, spring means in said pockets reacting between said base and said rods normally to urge said housing toward said pressure applying means, and platen members slidably mounted in said housing in position to engage in the welt crease of a shoe located in said press.

5. A shoe press having a base, an inflatable pressure applying pad supported by said base, means for supporting a shoe against the pressure exerted by said pad, a housing at the toe end of said base, said base having spring pockets at opposite sides thereof underlying said housing, 10 headed rods passing through said housing and slidably into said pockets, spring means in said pockets reacting between said base and said rods normally to urge said housing toward said pad, and platen members slidably mounted in said 15 housing in position to engage in the welt crease of a shoe located in said press.

6. In a shoe apparatus having means for applying pressure to the bottom of a shoe, a welt hold-down device comprising a housing having 20 upper and lower confining plates, a pair of platens pivotally joined at their forward ends and shaped to engage in the welt crease of a shoe positioned on said apparatus, said platens being 25 slidable between said plates and confined thereby 30 against vertical movement with respect thereto, each platen having a guide slot in the free end thereof, a fixed guide pin extending from said housing into each slot, additional guide means for said platens adjacent their pivotal joint, and 35 means for sliding said platens to accommodate shoes of varying sizes.

7. In a shoe apparatus having means for applying pressure to the bottom of a shoe, a welt hold-down device comprising a housing having 40 upper and lower confining plates, a pair of platens pivotally joined at their forward ends and shaped to engage in the welt crease of a shoe positioned on said apparatus, said platens being 45 confined between said plates and confined thereto by against vertical movement with respect thereto, each platen having a guide slot in the free end thereof, headed guide pins removably threaded into one of said confining plates in position respectively to extend within said guide slots, a

pin projecting from one of said platens in the vicinity of its pivotal joint, one of said plates having a groove embracing and slidably guiding said last named pin, and means for sliding said platens to accommodate shoes of varying sizes. 5

8. In a shoe apparatus having means for applying pressure to the bottom of a shoe, a welt hold-down device comprising a housing having upper and lower confining plates, a pair of platens pivotally joined at their forward ends and shaped to engage in the welt crease of a shoe positioned on said apparatus, said platens being slidably confined between said plates, each platen having a guide slot in the free end thereof, a guide pin extending from said housing into each slot, a link, a pin connecting said link with one of said platens adjacent its pivotal joint, said pin having a projecting portion, one of said confining plates having a guide groove slidably accommodating the projecting portion of said 15 connecting pin, and an operating lever connected with said link for moving said platens.

9. In a shoe apparatus having means for applying pressure to the bottom of a shoe, a welt hold-down device comprising a housing having 25 upper and lower confining plates, a pair of platens pivotally joined at their forward ends and shaped to engage in the welt crease of a shoe positioned on said apparatus, said platens being 30 slidably confined between said plates, each platen having a guide slot in the free end thereof, a guide pin extending from said housing into each slot, a link, a pin connecting said link with one of said platens adjacent its pivotal joint, said pin having a projecting portion, one 35 of said confining plates having a guide groove slidably accommodating the projecting portion of said connecting pin, an operating link connected with said link for moving said platens, and spring means normally urging said housing 40 toward said pressure applying means.

10. In a sole attaching apparatus, a pad support, a pad upon the support, a yoke sustained by the pad support, heel and toe supports sustained by the yoke, and a welt hold-down sustained by 45 the pad support independently of the yoke and of the heel and toe supports.

WILLIAM C. CARD, JR.
